ATTORNEY

UNITED STATES PATENT OFFICE

HAROLD W. FLETCHER, OF HOUSTON, TEXAS, ASSIGNOR TO HUGHES TOOL COMPANY,
OF HOUSTON, TEXAS, A CORPORATION OF TEXAS

PLUNGER LIFT EQUIPMENT

Application filed November 21, 1931. Serial No. 576,525.

My invention relates to plunger lift apparatus for raising liquid from deep wells, wherein gas or air pressure is employed in lifting the plunger with its load of liquid to the surface. It is designed as an improvement particularly of the device shown in the prior application of Norman H. Ricker Serial Number 443,013 filed April 10, 1930, patented February 9, 1932, No. 1,844,074.

10 It is an object of the invention to provide a device whereby the plunger may be retained at the upper end of its stroke by the pressure of the gas behind the load until the charge of gas has approximately exhausted. I desire to prevent the plunger from dropping into the rising blast of gas and being blown back again and also to prevent the falling of the plunger too quickly to the bottom before a head of liquid has risen above the plunger stop at the lower end of the tubing.

15 20 25

I so construct the outlet for the fluid from the eduction tube that the gas pressure on the plunger will serve to hold it in position against the side of the tube and thus prevent it from falling.

20 25 30

In the drawing herewith, Fig. 1 is a side view, largely in central vertical section, illustrating the application of the invention to the upper end of the installation.

Fig. 2 shows a central vertical section of the lower end of the eduction tube, in position in the well.

Fig. 3 is a transverse section on the plane 3—3 of Fig. 1.

35 The well in which my device may be employed is equipped with a casing 1 which extends some distance into the well. A special casing head 2 is connected with the upper end of the casing, said head having a lateral pipe 4 connected therewith with a control valve 5 in said pipe. The pipe furnishes an inlet or outlet for pressure fluid such as gas when desired or when the pressure of gas in the well is insufficient.

40 45 50

Another pipe 12, joined to the casing, furnishes an outlet for the fluid being pumped. The upper end of the casing head is closed by a bonnet 3, the upper end of which is threaded to receive the upper extension 7 upon the eduction tube 8. Said extension is

threaded at 6 to screw into said casing head and form a seal therewith.

Said tubing extension 7 is equipped with a valve 10 by means of which the plunger may be entrapped when desired in the upper end 55 9 of the tube which is closed by a cap 12.

The eduction tube 8 has a head 13 supported upon a shoulder 14 in the casing head and forming a seal therewith. The upper end 60 of the head 13 has a sliding fit with the tubing extension 7, and said extension is formed with outlet openings 15 therein on one side only and extending along the extension for approximately the full length of the chamber 16 within the casing head. 65

The lower end of the eduction tube 8 is connected with a strainer cap 17 by a special coupling 18, having a cross shaped stop member 19 therein.

70 The plunger 20 is of the usual construction. It has a tubular body connected at its lower end to a head 21 forming a support for the valve 23 when said valve is open and spaced below the valve seat 22. A stem 24 on the valve projects below the support to engage the stop member 19 when the plunger drops to the bottom.

75 80 85

In the operation of the device the plunger in dropping to the bottom has its valve 23 open. It will fall through the head of liquid above the stop member and when the bottom is reached, the contact of the valve stem with the stop will close the valve. Ordinarily there will be gas from the well accumulating in the well and when the pressure has reached a sufficient value to lift the plunger and its load, the plunger will rise and discharge the liquid through the outlet openings 15 to the discharge line 11. The plunger will be 90 forced past the openings into the closed upper end of the extension where the fluid is compressed above it opening the valve.

95 100

The plunger will then start to fall and will encounter the gas escaping from behind the plunger. This gas is escaping at one side only of the tube and will force the plunger against the outlet openings and hold it there, obscuring some of the openings, until the gas has mostly escaped and the pressure is re-

duced so as to allow the plunger to continue its fall.

- 5 The plunger will be thus delayed until most of the gas has escaped and the head of liquid at the bottom has risen in the eduction tube above the stop 19 to obtain sufficient load for the next stroke. In this way the plunger will not strike a dry seat at the bottom and thus injure the apparatus. Also there will be 10 no danger of the plunger being blown back by the escaping gas into the upper end of the tubing extension. The operation of the device will be smooth and uniform, and injury to the equipment will be avoided.
- 15 15. What I claim as new is:
1. A plunger lift device including a well casing, an eduction tube therein, a casing head sealed about said tube at the upper end of said head, a swab plunger operating in 20 said tube, said tube having outlet openings therein on one side only, whereby the fluid pressure below said plunger will tend to hold said plunger against said openings.
  2. In a plunger lift device, a well casing, a 25 casing head thereon, an eduction tube in said casing projecting through said casing head and secured to the upper end thereof, a discharge line connected with said casing head, said tube being formed with openings at one 30 side only, a plunger operating from the lower end to the upper end of said tube through gas pressure, said gas pressure tending to hold said plunger against said openings until said gas pressure is approximately exhausted.
  3. A fluid lift device including a well casing, a casing head thereon, an eduction tube in said casing, a plunger operated by pneumatic pressure in said tube, the discharge end 40 of said eduction tube being perforated to allow outlet of fluid at one side only, whereby the escape of pneumatic pressure will tend to hold said plunger against said perforated outlet.
  4. In a plunger lift, a well casing, an eduction tube therein, a plunger adapted to be raised with its load of liquid from the lower end of said tube to the upper end thereof by pneumatic pressure, a discharge line from 50 said casing, and outlet openings in said tube to said discharge line at one side of said tube, the remainder of said tube adjacent its upper end being imperforate.
  5. In a plunger lift, a well casing, an eduction tube therein, a plunger adapted to be raised with its load of liquid from the lower end of said tube to the upper end thereof by pneumatic pressure, a discharge line from 55 said casing, and means automatically operating responsive to fluid pressure in said tube to restrain the downward movement of said plunger until the pneumatic pressure behind said plunger has been approximately exhausted.
  6. In a plunger lift, a well casing, an eduction tube therein, a plunger adapted to be raised with its load of liquid from the lower end of said tube to the upper end thereof by pneumatic pressure, a discharge line from 60 said casing, and means actuated by said pneumatic pressure to restrain the downward movement of said plunger until the pneumatic pressure behind said plunger has been approximately exhausted.

7. In a plunger lift, a well casing, an eduction tube therein, a plunger movable by fluid pressure from the lower to the upper end of said tube, outlets from said tube for fluid arranged so that escaping fluid will hold said plunger adjacent said openings until said fluid has been approximately exhausted. 70

In testimony whereof, I hereunto affix my signature this the 2d day of November, A. D. 1931.
